US00D767587S

(12) **United States Design Patent** (10) **Patent No.:** **US D767,587 S**
Jou (45) **Date of Patent:** **** Sep. 27, 2016**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventor: **Min-Jee Jou**, Yongin-si (KR)

(73) Assignee: **Samsung Electronics Co., Ltd.**,
Suwon-si (KR)

(**) Term: **14 Years**

(21) Appl. No.: **29/476,320**

(22) Filed: **Dec. 12, 2013**

(30) **Foreign Application Priority Data**

Sep. 3, 2013 (KR) 30-2013-0045295

(51) **LOC (10) CI.** **14-04**

(52) **U.S. Cl.**

USPC **D14/485**
